DESIGN FOR A BOWLING BALL RACK OR THE LIKE

Robert E. Kennedy, Chicago, Ill., assignor to The
Brunswick-Balke-Collender Company, Chicago,
Ill., a corporation of Delaware

Application January 16, 1942, Serial No. 105,234

Term of patent 14 years

To all whom it may concern:

Be it known that I, Robert E. Kennedy, a citizen
of the United States, residing in the city
of Chicago, county of Cook, State of Illinois, have
invented a new, original, and ornamental Design
for a Bowling Ball Rack or the Like, of which the
following is a specification, reference being had
to the accompanying drawing, forming a part
thereof.

Figure 1 is a front elevational view of a bowling

ball rack or the like, showing my new design; and
Figure 2 is a perspective view thereof on a
larger scale.

The dominant features of the design are shown
in full lines.

I claim—

The ornamental design for bowling ball rack
or the like, as shown and described.

ROBERT E. KENNEDY.
